UNITED STATES PATENT OFFICE

159,153

SAMOVAR

Manuel J. Jacobs, San Francisco, Calif.

Application October 19, 1948, Serial No. 149,192

Term of patent 14 years

(Cl. D44—26)

To all whom it may concern:

Be it known that I, Manuel J. Jacobs, a citizen of the United States, residing at No. 1200 35th Avenue, in the city and county of San Francisco, State of California, have invented a new, original, and ornamental Design for a Samovar, of which the following is a specification, reference being had to the accompanying drawing, forming part thereof.

Fig. 1 is a front elevational view of a samovar showing my new design;

Fig. 2 is a side elevational view; and

Fig. 3 is a top plan view thereof.

I claim:

The ornamental design for a samovar, as shown.

MANUEL J. JACOBS.
